UNITED STATES PATENT OFFICE.

FRANK FRUSTAGLIO, OF SOUTH PORCUPINE, ONTARIO, CANADA.

MATCH-STRIKING SURFACE FOR PIPES.

1,206,213.

Specification of Letters Patent. Patented Nov. 28, 1916.

Application filed April 1, 1916. Serial No. 88,811.

To all whom it may concern:

Be it known that I, FRANK FRUSTAGLIO, a subject of the King of Italy, residing at South Porcupine, in the Province of Ontario and Dominion of Canada, have invented certain new and useful Improvements in Match-Striking Surfaces for Pipes, of which the following is a specification.

This invention relates to new and useful improvements in match striking surfaces for pipes.

The primary object of the invention is the provision of an article of manufacture consisting of a match striking surface 15 readily locked upon the stem of a smoking pipe.

A further object of the device is to provide for use upon a tobacco pipe of any ordinary construction, a striking surface for matches which is readily attached to the pipe stem by the owner thereof and may be removed and employed with a different pipe whenever desired.

A still further object is the provision of a device for increasing the pleasures of tobacco smoking by means of supplying a striking surface for matches removably carried by the pipe stem adjacent the point of desired ignition for the tobacco and whereby the pipe may be lighted more advantageously.

With these general objects in view and others that will appear as the nature of the invention is better understood, the same consists in the novel combination and arrangement of parts hereinafter fully described, illustrated in the accompanying drawings and then claimed.

In the drawings forming a part of this application and in which like designating characters refer to the corresponding parts throughout the several views:—Figure 1 is a side elevation of a pipe provided with the present device. Fig. 2 is an enlarged elevational view of the opposite side of the pipe stem from that illustrated in Fig. 1. Fig. 3 is a transverse sectional view through the pipe stem taken upon line III—III of Fig. 2. Fig. 4 is a similar enlarged sectional view of one side portion of the stem. Fig. 5 is a transverse sectional view of the band connection of the device taken upon line V—V of Fig. 2, and Fig. 6 is a perspective view of the complete device detached.

It will be understood that the present device broadly comprises a striking plate 10

designed for flat locking engagement with any desirable portion of a tobacco pipe such as the stem 11 of the pipe 12 in connection with which the pipe is herein illustrated, the 60 said pipe being of the general type having a tobacco receiving bowl 13 and a mouth-piece 14.

The said striking plate 10 is preferably of slightly arcuate form in cross section, 65 as best illustrated in Fig. 6 of the drawings and is provided with oppositely extending attaching bands 15 and 16 projecting laterally substantially midway of its opposite ends 17, the said bands having a general 70 curvature corresponding to that of the plate 10.

As an article of manufacture, the device is shown in its complete form in Fig. 6 of the drawings, the said bands 15 and 16 terminating in laterally projecting arms or tabs 18 which are adapted to overlie the adjacent band when the two bands are operatively arranged in overlapping relation, the tabs 18 then forming loops for maintaining 80 the ends of the bands 15 and 16 in sliding relations whereby the diameter of the circular member or ring thus formed is readily changed. Locking teeth 19 are provided upon adjacent surfaces of the bands 15 and 85 16, the band member being adapted for slipping over the mouth-piece 14 and upon the pipe stem 11 when the bands are expanded and by forcibly decreasing the diameter of the ring formed by the two bands, the free 90 ends of the said bands will slide relatively of each other with the toothed portions 19 of each interlocking and maintaining the band members in their adjusted relations with the plate 10 securely seated in flat engagement with the stem 11 and with inwardly projecting pins 20 carried by the plate firmly embedded in the stem.

It being understood that the outer surface 21 of the plate 10 is roughened affording an 100 advantageous match striking surface and as positioned longitudinally upon the stem 11 in the manner heretofore set forth this roughened plate is advantageous in the striking of matches or lighting the tobacco 105 positioned within the pipe bowl 13. The teeth 19 coöperating with the pins 20 lock the plate 10 upon the stem 11 requiring the tabs 18 of one of the bands such as 16 to be bent outwardly and released before the plate 110 can be removed but which release of the tabs 18 will allow a relative lateral move-

ment of the band ends, thus breaking the engagement between the teeth 19.

While the form of the invention herein shown and described is what is believed to be the preferable embodiment thereof, it is nevertheless to be understood that minor changes may be made in the form, proportion and details of construction without departing from the spirit and scope of the invention as hereinafter claimed.

What I claim as new is:—

1. An article of manufacture consisting of a match striker comprising a striking plate having a roughened outer surface and being arcuate in transverse section, inwardly projecting pins carried adjacent the opposite ends of said plate, oppositely projecting mounting bands centrally carried by the

said plate having overlapping end portions having interlocking teeth upon their adjacent contacting surfaces, the said bands and plate being normally arranged in adjustable annular formation and laterally projecting tabs at the ends of the said bands overlying the adjacent band in loop forming arrangement.

2. A device of the class described comprising a scratch plate, curved bands carried by opposite sides thereof with the band ends overlapped, the opposed faces of the overlapped ends of the bands being notched to provide engaging teeth, and tabs carried by each band end adapted to be bent into engagement with the opposed band end.

In testimony whereof I affix my signature.

FRANK FRUSTAGLIO.
